UNITED STATES PATENT OFFICE.

CHARLES STENGEL, OF HAMILTON, OHIO.

BALL-COCK.

1,314,160.

Specification of Letters Patent. Patented Aug. 26, 1919.

Application filed March 15, 1919. Serial No. 282,794.

To all whom it may concern:

Be it known that I, CHARLES STENGEL, a citizen of the United States, residing at Hamilton, Butler county, Ohio, have invented certain new and useful Improvements in Ball-Cocks, of which the following is a specification.

This invention, pertaining to ball cocks, relates to improvements designed to increase 10 the accuracy and noiselessness in operation of this class of devices.

The improvements will be readily understood from the following description taken in connection with the accompanying drawings in which:

Figure 1 is a plan, and Fig. 2 a vertical section in the plane of line *a* of Fig. 1, of a ball cock embodying an exemplification of my improvements.

20 In the drawing:—

1, indicates the cock-body:

2, a chamber in the upper portion thereof:

3, a threaded shank at the base of the body, to serve in attaching the body to the 25 floor of a tank:

4, the inlet passage for the supply water, this passage extending axially through the shank and through a tube projecting up through the chamber 2 from the floor of 30 the chamber:

4^a, the tube referred to:

5, the upper end of the tube, this tube-end forming the valve-seat:

6, the outlet passage leading from chamber 2:

7, a cap having a flange loosely surrounding the upper end of the outlet:

8, an axial screw anchored into the outlet and passing loosely through the cap:

40 9, a spring, as of elastic rubber, surrounding the screw between the cap and the head of the screw:

10, a pivot-bearing bolted to the top of the body:

45 11, an elastic gasket, as of rubber, interposed in the joint between the body and the pivot-bearing, this gasket being provided with a central aperture:

50 12, a tube loosely surrounding the upper end of tube 4^a and projecting down through the perforation in the gasket and having a peripheral flange engaging over the margin of the perforation:

55 13, a cap screwed on the upper end of tube 12:

14, a disk, as of rubber, secured to the up-

per end of tube 12 by its cap, this disk forming the valve which seats downwardly on the upper end of tube 4^a:

15, a pivot carried by the pivot-bearing at 60 right angles to the axis of tube 4^a:

16, a lever mounted on this pivot and having its inner end projecting over cap 13:

17, a screw adjustable in lever 16 and impinging on cap 13; and 65

18, the ball stem, which is to be assumed as being provided on its outer end with the usual float ball.

The parts are shown with the valve closed, thus preventing the admission of 70 water through the supply passage, and the valve is to be assumed as being held closed by the buoyant action of the float, as usual.

When the float descends, due to the lowering of the level of the water in the tank, 75 the valve is permitted to rise and open under the influence of the pressure of supply. The water entering through the opened valve passes down in the space between tubes 12 and 4^a and reaches chamber 2, the 80 pressure of the water in the chamber distending the central portion of the gasket upwardly so that it makes a tight joint with the flange surrounding tube 12. The water, under accumulated pressure in chamber 2, 85 presses upwardly on cap 7, which acts as an outlet valve, the departing water leaving the outlet in the form of a flat spray which is turned downward by the skirt of cap 7 and is at liberty to enter the tank. Spring 90 9 resists the opening of the outlet valve, and its tension may be adjusted by screw 8. The result is that the outlet may deliver its water in a comparatively noiseless manner.

Screw 17 may be employed in adjusting 95 the height of the float when valve 14 is closed. Disk 14, forming the inlet valve, may be renewed by removing cap 13 from tube 12. Pivot 15 being removed, permits the removal of lever 16 and the ready withdrawal of tube 12 and the inlet valve, the pivot-bearing 10 being provided with a large central aperture to permit such withdrawal.

I claim:—

1. A ball-cock comprising, a body having 105 a chamber provided with an outlet and with an inlet extending above the top of the chamber, an apertured pivot-bearing secured to the top of the body, a perforated gasket disposed between the pivot-bearing and the body, an inlet valve seating on the upper end of the inlet and loosely surrounding the 110

same and projecting down through the perforation in the gasket and having a flange engaging over the gasket, and a float lever pivoted to the pivot-bearing and having its inner end arranged to act downwardly upon the valve, combined substantially as set forth.

2. A combination such as recited in claim 1 when combined with an adjusting screw 10 engaging between the inlet valve and the inner end of the float-lever, substantially as set forth.

3. A combination such as recited in claim 1 when the inlet valve is formed of a threaded tube provided with a cap screwed thereto and clamping a disk between the cap and the upper end of the tube, substantially as set forth.

4. A ball cock comprising, a body having a chamber provided with an inlet and with an outlet, an inlet valve for the inlet, and an outlet valve for the outlet, the outlet

valve being provided with a skirt loosely surrounding the outlet, substantially as set forth.

5. A ball cock comprising, a body having a chamber provided with an inlet and with an outlet, an outlet valve for the outlet, a headed adjustable axial screw at the outlet, an outlet valve playing loosely on said screw, 30 and a spring surrounding the screw over the outlet valve and under the head of the screw, substantially as set forth.

6. A ball cock comprising, a perforated elastic gasket, an inlet tube projecting 35 through the gasket, a tube loosely surrounding the inlet tube and engaging the gasket, and an inlet valve at the upper end of the last-mentioned tube and closing upon the inlet, substantially as set forth.

CHARLES STENGEL.
